TELEVISION SYSTEM

Charles Leslie Faudell, near Stoke Poges, England, assignor to Electric & Musical Industries Limited, Hayes, Middlesex, England, a company of Great Britain

Application January 18, 1938, Serial No. 185,493
In Great Britain January 20, 1937

5 Claims. (Cl. 178—7.3)

This invention relates to television systems, and is particularly concerned with circuits for obtaining synchronism between the operation of scanning at a receiver with that at a transmitter.

In the specification of British Patent #455,375, the problems involved in obtaining synchronism are discussed, and alternative synchronising pulse separating circuits are described, such circuits being for use in television systems employing frame pulses of relatively long duration and line pulses of relatively short duration, but of the same amplitude. In certain of the arrangements described in the specification, a condenser is charged through a resistance and shunted by a valve which is positively biased, and is, therefore, conducting in the intervals between pulses. The condenser charges during pulses and a saw-tooth voltage waveform is produced, the pulses of which are of duration equal to that of the pulses producing them but of greater amplitude in the case of the longer frame pulses. By applying both derived saw-teeth pulses to an amplitude selecting device the pulses of larger amplitude operate to produce pulses which are applied to the frame deflecting apparatus.

In one arrangement described in the specification referred to, an inductance is inserted in series with a resistance in the anode lead of the valve and the time constant of the coil and resistance are made longer than the duration of a frame pulse. The synchronising pulses are applied to the valve which is so negatively biased as to be conducting only when the synchronising pulses are applied in the positive sense between the grid and cathode of the valve. Current flowing through the valve on the application of a synchronising pulse builds up in the inductance and on the cessation of the pulse the voltage set up across the resistance suddenly changes and the saw-tooth voltage pulse thus produced is taken off from terminals, one of which is connected to the junction between the inductance and the resistance and the other to the cathode of the valve. The saw-tooth pulses due to the frame synchronising pulses will be of larger amplitude than those due to the strip or line synchronising pulses and will operate frame waveform deflecting apparatus which is not responsive to the smaller amplitude saw-tooth pulses derived from the line synchronising pulses.

The object of the present invention also is to provide improved line and frame pulse separating circuits in which irregular operation due to

the effect of adjacent pulses upon each other is avoided or reduced.

According to the present invention, converting means for producing derived frame and strip pulses from frame and strip synchronising pulses include an inductance through which passes current controlled by a controlling device, a unilaterally conducting device being operatively connected with this inductance in such a manner that current normally flowing through said unilaterally conducting device ceases to flow on the application of frame synchronising pulses to the controlling device, the derived frame pulses being obtained from the output terminal of the unilaterally conducting device.

In particular circuit arrangements embodying the invention the controlling device is a thermionic valve which is normally conductive but is rendered non-conductive on the application to it of either frame or strip synchronising pulses, and the unilaterally conducting device provides a shunt path across the inductance and thermionic valve, this unilaterally conducting device being normally conductive but rendered non-conductive on the application of the frame synchronising pulse to the thermionic valve. The inductance is connected in series with a resistance, the time constant of the inductance and resistance combination being long compared with the duration of a frame synchronising pulse.

The inductance may be connected directly in the anode lead of the thermionic valve and the unilaterally conducting device may consist of a diode valve, the anode of which is connected to the end of the inductance remote from the anode of the valve, a positive potential being applied to the cathode of the diode such that current flows through the diode until a frame synchronising pulse is applied to the thermionic valve. The diode may be provided with a second anode connected to the end of the inductance adjacent the anode of said thermionic valve in order to provide a short circuit path across the inductance on the conclusion of a frame synchronising pulse and so to damp oscillation due to the coil which might otherwise occur.

In a modification of the present invention an inductance and a unilaterally conducting device constitute a shunt path across a controlling device. The controlling device may be a thermionic valve which is normally non-conductive but is rendered conductive on the application to it of either frame or strip synchronising pulses, and the unilaterally conducting device may be a diode valve the cathode of which has applied to it

a positive potential such that current flows through the diode until a frame synchronising pulse is applied to the valve. A resistance may be connected between a source of voltage and the anode of the thermionic valve or a tapping point in the inductance. In any of the arrangements employing a screen grid thermionic valve as a controlling device, strip frequency pulses derived from strip frequency synchronising pulses applied to the control grid of said valve may be taken from the screening grid of the valve.

In order that the invention may be more clearly understood and readily carried into effect, some circuit arrangements embodying the invention will now be described more fully by way of example with reference to the accompanying drawings in which:

Figs. 1, 2, 4, 5 and 6 are alternative forms of circuit, and

20 Fig. 3 represents transient voltage impulses.

Referring to Fig. 1 of the drawings, the incoming signals are applied to the control grid of a screen grid valve 1 through a coupling condenser 2 shunted by a leak resistance 3. The control grid of the valve 1 is so biased relative to the cathode by means not shown in the drawing that no anode current flows in the absence of signals. The signals are applied to the valve 1 in such a sense that only the synchronizing signals drive the control grid sufficiently positive to cause the valve to conduct. An inductance 4 and resistance 5 are connected in series in the anode lead of the valve 1 and have a time constant which is long compared with the duration 35 of a frame pulse.

The anode of a diode valve 7 is connected to the junction 6 between the inductance 4 and resistance 5, and the cathode of this diode is maintained at a constant potential of the order 40 of 60 volts, derived from a resistance 8 connected across the high tension source of supply of 250 volts. The positive potential at which the cathode of the diode is maintained is such that a considerable current normally flows through the diode.

45 During the occurrence of a line pulse, increasing current flows in the valve 1 and the current through the diode 7 decreases owing to the decreasing voltage at the anode of the diode, the 50 sum of the valve and diode currents being substantially constant. On account of the short duration of the line pulse, and the long time constant of the anode impedance, the current in the valve does not rise to a value greater than 55 that initially flowing in the diode, so that the latter remains conducting throughout, and the voltage of its anode only varies slightly. On the occurrence of a frame pulse of long duration, however, the current in the valve increases to such 60 an extent that the potential of the junction 6, and thus the anode of the diode 7, fall below the potential of the cathode of the diode. The diode is thus rendered non-conductive.

Thus, assuming that there is no stray capacity, 65 the voltage waveform appearing at the junction 6 will take the form of a series of triangular pulses of negative sense corresponding to the frame pulses. These saw-teeth pulses are fed through the condenser 9 to a scanning oscillator circuit.

In the arrangement shown in Fig. 2 of the drawings, the diode cathode is connected through the winding of a transformer 10 coupled to the scanning oscillator, to a suitable positive potential as before. In this arrangement the diode re-

5 mains conducting during the occurrence of line pulses and is rendered non-conducting at the occurrence of frame pulses so that a voltage pulse of considerably greater amplitude is induced in the secondary winding.

Theoretically, any values for the inductance 4 and resistance 5 to give a suitable time constant may be selected, but owing to the distributed capacity of the coil 4, a tuned circuit is formed having a definite decay period so that after each 10 synchronising pulse, the time taken for the pulse on the anode of the valve to return to zero will depend upon the natural frequency of this tuned circuit and its damping. In a system employing interlacing, the return to zero must, in order that 15 the interlacing should be accurate, be effected within a half line period.

The waveforms shown in Figure 3 of the drawings serve to illustrate the effect of the selection 20 of inductances of different values.

The waveforms represented at a, b and c correspond with the use of inductances 50, 10 and 2 henries respectively, while that shown at d is obtained when a damped inductance of 2 henries is employed. Only the waveform shown at d is 25 really satisfactory. It thus appears that the inductance 4 must be small and suitably damped, and a coarse iron core may be employed to provide suitable damping. Again, the resistance 5 should be high. The damping may be improved 30 by connecting the anode of the diode 7 to a tapping point in the resistance 5, although in such a case there will be some loss of pulse amplitude.

In the arrangement shown in Figure 4 of the drawings, the diode 7 is provided with an additional anode which is connected directly to the anode of the valve 1. This connection ensures that when the anode of the valve 1 rises above the steady potential of the diode cathode at the 40 conclusion of a pulse, there is a direct connection of the anode of the valve through the diode to the large condenser 11, thus preventing large 45 amplitude oscillation. It will be seen that this arrangement ensures complete isolation from any deleterious effects between adjacent synchronising pulses and the operation of the separating circuit is quite regular. The arrangement shown in Figure 4 is found to be effective even if the inductance 4 is undamped. It is advantageous 50 to employ a lightly damped inductance having small self capacity.

Referring now to Fig. 5 of the drawings, the incoming signals are applied to the control grid of a screen grid valve 1 which is so biased relatively to the cathode by means not shown in the drawings and the signals are applied in such a sense that only the synchronising signals drive the control grid sufficiently positive to cause the valve to conduct. A resistance 14 is connected 60 in the anode lead of the valve 1 and a choke coil 15 is also connected directly to the anode lead 18 and to a terminal 19 of a frame frequency oscillator not shown in the drawings. The anode 20 of a diode 17 is connected to the terminal 19 and 65 the cathode of the diode is maintained at an intermediate positive potential by means not shown in the drawing. When valve 1 is non-conducting the diode 17 is conducting and current flows through the choke 15 from the lead 18 to the anode 20 of the diode. When the impedance of the valve 1 is reduced to a low value by the application of a positive synchronising pulse to its grid, its anode falls to a very low potential 70 and a large voltage is set up across the choke 15 75

and causes a constant rate of decrease of the current flowing through it into the diode 17. If the positive pulse applied to the grid of the valve 1 is of short duration, sufficient time may not elapse for the current through the choke 15 to fall to zero and to cause the diode to become non-conducting. A positive pulse of longer duration such as a frame pulse, will result in the diode becoming non-conducting and negative pulses will therefore be set up at the anode of the diode 17 only in response to those positive pulses applied to the grid of the valve 1 which exceed a certain predetermined duration. The values of the resistance 14, the inductance of the choke coil 15 and the voltage applied to the cathode of the diode 17 will determine the duration of a positive pulse applied to the grid of valve 1 which will result in the diode 17 becoming non-conductive and these values may be selected accordingly.

20 The form of the pulses set up at the terminal 19 may be modified by connecting a condenser 22 between the anode 20 of the diode and earth. This condenser will have no effect on the operation of the circuit as already described because during the decrease of current through the choke coil 15, the condenser 22 is effectively short circuited by the low impedance of the diode and is therefore inoperative. Additional integration of the pulses can be obtained by the insertion of another condenser 23, which serves to delay the fall of potential of the anode 18 when the valve is made non-conducting, but the use of this extra condenser is also not essential to the operation of the circuit.

35 A more detailed form of circuit is shown in Fig. 6 of the drawings. The connections for taking off the line synchronising pulses are shown added to those of Fig. 5 and include a resistance 25 of 500 ohms and a condenser 26 of .5 microfarads connected between the screen grid of valve 1 and a terminal 28 of a line frequency oscillator not shown in the drawings. The screen grid is also shown connected to a source of high tension voltage through a resistance 30 of .5 of a megohm.

40 The positive biasing potential applied to the cathode of the diode is derived automatically by means of a resistance 32 of 50,000 ohms shunted by a condenser 33 of four microfarads inserted in the cathode lead. A condenser 35 of .0005 microfarad is connected directly across the valve 1, but no condenser equivalent to the condenser 22 in Fig. 5 is included as the stray capacities of a frame frequency blocking oscillator connected to the terminals 37 and 38 through a condenser 19 of .01 microfarad, render the insertion of a condenser unnecessary.

45 The operation of this circuit is similar to that described with reference to Fig. 5, the synchronising pulses again being applied in the positive sense to the control grid of valve 1. Instead of the direct current coupling to the grid of valve 1 shown in Fig. 5, an alternating current coupling is shown in Fig. 6, a condenser being inserted in the grid lead with a shunt resistance to earth, the limiting valve 1 in this case constituting a self re-established bias limiting device. Again, instead of the single anode diode shown in Fig. 5, a double diode is shown in Fig. 6, the diode being self biasing by virtue of the resistance 32. The time constant of the resistance 32 and condenser 33 is arranged to be long compared with a line period. The second anode 20a of the diode serves to damp the oscillation of the choke coil 15 in a manner similar to that described with reference

5 to the arrangement shown in Fig. 4 of the drawings.

In a modified circuit arrangement the resistance 14 instead of being connected directly to the anode of the valve 1 may be connected to a tapping point in the choke coil 15, the tapping being, for example, mid-way between the ends of the choke coil.

10 While in Fig. 6 the derived strip pulses are taken from the screening grid of the valve 1, these derived pulses can be taken from the anode of that valve. In this case the condenser 35 will be omitted in order to retain the sharp wave front, and in order to reduce the effects of interference, a further pulse amplitude limiting valve 15 may be inserted.

15 In operating certain saw-tooth waveform generating circuits including gas discharge valves, the synchronising pulse should preferably be applied in the positive sense. Each or both of the 20 anodes in the diode 17 can be replaced by the control grids of a pair of phase reversing valves which are biased to a potential such that the control grids operate in substantially the same manner as the anodes of the diode 17. A further 25 advantage is that the lower region of the synchronising pulse which is most liable to contain interference will be further limited and again the possibility of cross-coupling will be reduced.

I claim:

1. In a television receiver wherein a single signal series of line and frame synchronizing impulses and picture signals are received comprising, a picture signal separator tube having a cathode, a control electrode and an anode, a 35 source of potential, means for connecting the negative terminal of said source to said cathode, means including a load circuit comprising a series-connected resistance and inductance for connecting the positive terminal of said source to said anode, means for maintaining a predetermined negative bias on the control electrode with respect to the cathode, means for applying the received synchronizing impulses and picture signals to said control electrode to render said tube 40 conducting throughout the duration of each synchronizing impulse only, a diode including a cathode and an anode, means for connecting the anode of said diode to the junction of said resistance and inductance, means for maintaining the 45 cathode of said diode positive with respect to the cathode of said separator tube by a predetermined amount, whereby the current drawn by said diode may be caused to vary by reason of the voltage drop in the separator tube load circuit 50 when synchronizing impulses are applied to said tube, and an output circuit coupled to said diode.

2. In a television receiver wherein line and frame synchronizing impulses and picture signals are received, the frame impulses being of greater duration than the line impulses and all synchronizing impulses being of greater intensity than any picture signal, comprising a picture signal separator tube having a cathode, a control electrode and an anode, a source of potential, means for connecting the negative terminal of said source to said cathode, means including a load circuit comprising a series connected resistance and inductance for connecting the positive terminal of said source of potential to said anode, 65 means for maintaining a predetermined negative bias on the control electrode with respect to the cathode, means for applying the synchronizing impulses and picture signals to said control electrode to render said tube conducting upon the 70 75

occurrence of each synchronizing impulse, a diode including a cathode and an anode, means for connecting the anode of said diode to the junction of said resistance and inductance, means 5 for maintaining the cathode of said diode positive with respect to the cathode of said separator tube by an amount such that the current drawn by said diode will be reduced to zero by reason of the voltage drop in the separator tube load circuit 10 when frame synchronizing signals are applied to said discharge tube, and an output circuit coupled to said diode.

3. In a television receiver wherein line and frame synchronizing impulses and picture signals 15 are received, the frame impulses being of greater duration than the line impulses and all synchronizing impulses being of greater intensity than any picture signal, comprising a picture signal separator tube having a cathode, a control electrode and an anode, a source of potential, means for connecting the negative terminal of said source to said cathode, means including a load circuit comprising a series connected resistance and inductance for connecting the positive terminal of said source of potential to said anode, means for maintaining a predetermined negative bias on the control electrode with respect to the cathode, means for applying the synchronizing impulses and picture signals to said control electrode 20 to render said tube conducting upon the occurrence of each synchronizing impulse, a diode including a cathode and an anode, means for connecting the anode of said tube to the junction of said resistance and inductance, means for 25 maintaining the cathode of said diode positive with respect to the cathode of said separator tube by a predetermined amount, whereby the current drawn by said diode may be caused to vary in accordance with the voltage drop in the load circuit of the separator tube as determined by the current drawn by said separator tube, the potential of the cathode of said diode being such that the diode current is reduced to zero upon the application of a frame synchronizing impulse to 30 said separator tube, and an output circuit responsive to the potential across said diode.

4. In a television receiver wherein line and frame synchronizing impulses and picture signals 35 are received as a single signal series, the frame impulses being of greater duration than the line impulses and all synchronizing impulses being of greater intensity than any picture signal, comprising a picture signal separator tube having a cathode, a control electrode and an anode, a source of potential, means for connecting the 40

negative terminal of said source to said cathode, means including a load circuit comprising a series connected resistance and inductance for connecting the positive terminal of said source of potential to said anode, means for maintaining a predetermined negative bias on the control electrode with respect to the cathode, means for applying the synchronizing impulses and the picture signals to said control electrode to render 5 said tube conducting only upon the occurrence of each synchronizing impulse, a diode including a cathode and an anode, means for connecting the anode of said diode to the junction of said resistance and inductance, means for maintaining the cathode of said diode positive with respect to the cathode of said separator tube by an amount such that the voltage drop in the lower circuit of said separator tube will be sufficient to reduce the diode current to zero when a frame synchronizing impulse is impressed upon said separator tube, 10 and an output circuit responsive to the current drawn by said diode.

5. In a television receiver wherein line and frame synchronizing impulses and picture signals 15 are received as a single signal series, the frame impulses being of greater duration than the line impulses and all synchronizing impulses being of greater intensity than any picture signal, comprising a picture signal separator tube having a cathode, a control electrode and an anode, a source of potential, means for connecting the negative terminal of said source to said cathode, means including a load circuit comprising a series connected resistance and inductance for connecting the positive terminal of said source of potential to said anode, means for applying the synchronizing impulses and the picture signals to said control electrode to render said tube conducting only during the synchronizing impulse intervals, a diode including a cathode and a pair 20 of anodes, means for connecting one of the anodes of said diode to the junction of said resistance and inductance, means for connecting the other anode of said diode to the anode of said separator tube, means for maintaining the cathode of said diode positive with respect to the cathode of said separator tube, by an amount such that the current drawn by said diode will be reduced to zero by reason of the voltage drop in the load circuit 25 of said separator tube when a frame synchronizing impulse is applied to the control electrode of said tube, and an output circuit coupled to said one anode and said cathode of the diode.

CHARLES LESLIE FAUDELL. 55
